ABSTRACT

A vibrator assembly for a concrete mold plate comprising a vibrator to be located by means of form wedging or form fitting within the mold plate to one or more partition walls thereof, said vibrator being provided with an elongated fitting member making it possible to secure the vibrator relatively deeply inside the mould by fixing the fitting element to the mold plate itself.

VIBRATOR ASSEMBLY FOR CONCRETE MOLD PLATES

This invention relates to a vibrator assembly for concrete mold plates comprising fitting elements in the mold plate and a vibrator.

Such mold vibrators which are attached, for example, to the surface of a mold plate are used for the packing of concrete material, particularly in packet and other vertically cast molds. There are also rod vibrators which are located inside the concrete itself. In addition, attempts have been made to locate vibrators inside mold plates, but because of assembly difficulties it has been necessary to place them near the edges of the mold plates, and the vibration effect has not been satisfactory.

An object of the invention is to eliminate the above-mentioned disadvantages, and to make a new type of vibrator assembly.

It is a general characteristic of an assembly in accordance with the invention that at least one housing, in which the vibrator can be located by means of either form wedging or form fitting, is fitted to one or more partition walls of the mold plate.

An assembly in accordance with the invention offers considerable advantages in comparison with earlier arrangements:

- the fitting of the vibrator is both simple and reliable
- the locating of the vibrator is easy
- the vibrator can be fitted at a great distance from the edges of the plate, giving better results
- the dimensions of the vibrator can be sufficiently reduced for it to be used with relatively thin mold plates.

The invention is described in greater detail below with the aid of the attached drawings in which:

FIG. 1 is a longitudinal cross-sectional view of a mold plate showing a vibrator assembly in accordance with the invention;

FIG. 2 shows the assembly of FIG. 1 through a cross-section along line 2-2 of the mold plate in FIG. 1; and

FIGS. 3 to 6 show the vibrator in various different forms.

In FIGS. 1 and 2, a housing of tube form 2 is fitted in apertures located in the partition walls 10, 11 of a mold plate 1. The inner surface of this housing 2 is tapered in the direction of the inner part of the mold plate 1 in such a fashion that the vibrator 3, whose outer surface follows the contours of the inner surface of the housing 2, is securely wedged in position.

The vibrator consists of a head 3, a shaft element 4 connected to the head and a fixing flange 8 which is, in turn, connected to the shaft. There is an opening 6 in the side wall of the mold plate 1 at the same level as housing 2, around which the fixing flange 8 of the vibrator is attached by means of bolts 7. The vibrator shown in FIGS. 1 and 2 is electrically operated, but the invention also permits the use of a vibrator operated by compressed air. It is desirable for the power transmission element 5 to pass through the shaft 4, but it can also be located outside it.

The means of fixing the vibrator 3 depends upon its form in accordance with the invention. Any of the following methods, form wedging (FIGS. 1 and 2), form fitting, or thread fixing, which can be accomplished from outside the mold plate can be used. Different shapes can be used, and thus the inner surface of the housing 2 and/or the outer surface of the vibrator 3 can

have the form of a tapering solid of revolution, a frustum of a cone, a truncated pyramid, a cylinder, a prism, or any similar type of shape (FIGS. 3-6).

The housing 2 can also consist of an opening in one of the partition walls 10, into which the vibrator 3 can be wedged. In addition the housing 2 can be made up of openings in two or more adjacent partition walls 10, 11. A suitable reinforcing collar can be mounted around the openings.

10 The housings 2 are fitted to the mold plates 1 during the manufacture of the plates. A housing 2 of tube-like shape will, for example, reinforce the mold plate as a whole when welded to partition walls 10 and 11.

As will be appreciated from the above, FIGS. 1 and 15 2 represent only one corner of a bigger mold plate having a generally box-like structure and being provided with at least one horizontal vibrator 3. When the mold is filled, the concrete to be vibrated will be situated between two or more, e.g., parallel, mold plates, i.e., outside the lateral sheets 13 and 14 (FIG. 2). The mold plate is reinforced with internal partition walls 10 and 11, which are parallel to each other and also parallel to the vertical edge plates 12. Finally, the mold plate is closed from its upper and the lower side by means of 20 horizontal edge plates 1. The cutouts 15 and 16 in the partition walls 10 and 11 provide a passage for the distribution ducts for heating water.

25 The vibrator 3 essentially becomes part of the mold plate when the mold plate is in function. In view of the easy detachment of the vibrators, however, the same vibrators may of course be used with different mold plates.

30 It is also possible to reverse the situation so that, contrary to the embodiment of FIGS. 1 and 2, the outer end of the vibrator has a bigger cross-section than the inner end. As appears in FIG. 5, the vibrator has a generally conical form, with longitudinal ridges 17 extending out of the conical surface. The housing has a cross-section corresponding to that of the vibrator in such a way that the minimum cross-section of the housing at 35 least equals the maximum cross-section of the vibrator. The vibrator can be inserted all through said housing, then turned about its axis, and finally pulled towards the aperture by means of a removable tube so that the ridges 17 will mate with those portions of the inner side of the housing having a smaller diameter.

40 What is claimed is:

1. A vibrator assembly for a concrete mold plate having at least one partition wall, said assembly comprising fixing elements on the mold plate and a vibrator, said fixing elements including at least one housing in which the vibrator is accommodated by means of form wedging or form fitting, said housing being attached to said 45 partition wall of the mold plate.

50 2. A vibrator assembly in accordance with claim 1 wherein the inner surface of the housing and the outer surface of the vibrator are of the same general shape.

3. A vibrator assembly in accordance with claim 2 55 wherein the inner surface of the housing and the outer surface of the vibrator have the form of a tapering solid of revolution.

4. A vibrator assembly in accordance with claim 3 60 wherein the inner surface of the housing and the outer surface of the vibrator have the form of the frustum of a cone.

65 5. A vibrator assembly in accordance with claim 2 wherein the inner surface of the housing and the outer

surface of the vibrator have the form of a truncated pyramid.

6. A vibrator assembly in accordance with claim 2 wherein the inner surface of the housing and the outer surface of the vibrator have a form at least approximating to a cylinder.

7. A vibrator assembly in accordance with claim 2 wherein the inner surface of the housing and the outer surface of the vibrator have a form at least approximating to a prism.

8. A vibrator assembly in accordance with claim 2 comprising corresponding screw threads on the vibrator and the housing.

9. A vibrator assembly in accordance with claim 1 wherein the housing consists of a cylindrically shaped element.

10. A vibrator assembly in accordance with claim 1 wherein the vibrator comprises a head, a shaft element connected to the head and a fixing flange which is connected to the shaft.

11. A vibrator assembly in accordance with claim 10 wherein the fixing flange is attached around an aperture provided in said plate.

12. A vibrator assembly in accordance with claim 11 comprising a power transmission element for the vibrator passing through the shaft.

13. A vibrator arrangement for a concrete mold plate having inner partition walls, comprising:

- a. at least one vibrator;
- b. fitting means for fixing the vibrator from outside the mold plate;
- c. a shaft element interconnecting the vibrator with said fixing means;
- d. means in the mold plate defining an aperture for the insertion of the vibrator in the plate; and
- e. means in the partition walls of the mold plate at least partially mating with the outer surface of the vibrator for locating the vibrator inside the mold plate by form wedging or form fitting.

14. A vibrator arrangement as claimed in claim 13 wherein the means in the partition walls comprises a separate housing.

15. A vibrator arrangement as claimed in claim 13 wherein the means for fixing the vibrator comprises a fixing flange.
